MINE CAR COUPLING

John L. Day, Keokee, Va.

Application April 24, 1934, Serial No. 722,182

1 Claim. (Cl. 213—190)

The present invention relates to new and useful improvements in mine car couplings and has for its primary object to provide, in a manner as hereinafter set forth, a device of this character which will function automatically to couple the cars when said cars are brought together, thus eliminating entirely the danger of injury to persons which now exists when the coupling is done manually.

Another very important object of the invention is to provide a mine car coupling of the character described embodying a novel construction, combination and arrangement of parts whereby the cars may be expeditiously disconnected when desired without the necessity for the person performing the operation getting between the cars or touching the coupling with his hands.

Other objects of the invention are to provide a mine car coupling of the character set forth which will be comparatively simple in construction, strong, durable, highly efficient and reliable in use, compact and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a mine car coupling constructed in accordance with the present invention.

Figure 2 is a view in top plan thereof.

Figure 3 is a detail view in perspective of the crank lever through the medium of which the cars are uncoupled.

Figure 4 is a view in vertical longitudinal section, taken substantially on the line 4—4 of Figure 2.

Figure 5 is a horizontal sectional view, taken substantially on the line 5—5 of Figure 4.

Referring now to the drawings in detail, it will be seen that the reference numeral 1 designates the adjacent end portions of a pair of conventional mine cars. The embodiment of the present invention which has been illustrated comprises a pair of substantially segmental bumpers 2 and 3 which are rigidly secured to the cars 1, as at 4. As best seen in Figure 2 of the drawings, the peripheries of the substantially segmental bumpers 2 and 3 are opposed to each other.

Rigidly secured, as by bolts 5, on top of the

bumper 2 is a block 6. The opposed faces of the block 6 and the bumper 2 have formed therein recesses which define a chamber 7, Figure 4, thru which a comparatively large vertical bolt 8 passes. The chamber 7 is for the reception of an elongated coupling link 9 through which the bolt 8 also passes. The reference numeral 10 designates coil springs which are mounted in sockets 11 provided therefor between the block 6 and the bumper 2 and which project into the chamber 7 for engagement with the link 9 for yieldingly maintaining said link 9 in a longitudinally projecting position, as best seen in Figure 5 of the drawings.

By comparison of Figures 4 and 5 it will be noted that the upper and lower walls of the chamber 7 hold the link 9 against vertical deflection, and that the springs 10 housed in the sockets 11 by bearing against opposite sides of the inner end portion of the link 9 are adapted to yieldingly maintain said link in and tend to return it to the position shown in Figure 5.

The above will be better understood when it is stated that on lateral swinging of the link 9 in either direction, the spring 10 against which the link is swung will be compressed and tensioned, and then on release of the link the expansion of the said spring 10 will move the link back to the position shown in Figure 5. This operation will take place when the link 9 is arranged relatively to the spring 10 as shown in Figure 5.

A block 12 is rigidly secured on the bumper 3 by bolts 13. The block 12 and the bumper 3 are formed to provide a throat 14 for the reception of the coupling link 9. The block 12 is further provided with a chamber 15 with which a slot 16 communicates. A substantially V-shaped latch 17 is operable in the chamber 15, a pivot pin 18 passing through the free end portion of one of the legs of said latch. As illustrated to advantage in Figure 4 of the drawings, the latch 17 is engageable in the link 9 for retaining said link in the throat 14. The bumper 3 is formed to provide a shoulder 19 with which the latch 17 is engaged when in operative position.

The reference numeral 20 designates a crank lever which is journaled in bearings 21 on the end of the car 1 which carries the bumper 3. The inner end of the crank lever 20 is connected by a chain 22 to the free end of the substantially V-shaped latch 17 which projects upwardly through the slot 16.

It is believed that the operation of the coupling will be readily apparent. When the cars

are brought together the link 9 which, as hereinbefore stated, is yieldingly maintained in a longitudinal position by the coil springs 10, enters the throat 14 and raises the latch 17, the construction and arrangement of said latch 17 being such as to facilitate this operation. As soon as the adjacent end portion of the link 9 passes the latch 17 said latch 17 drops by gravity through the link and into engagement with the shoulder 19 and the coupling operation is thus completed. To uncouple the cars the crank lever 20 is manually actuated in a manner to raise the latch 17 and permit withdrawal of the coupling link 9. The rounded or substantially segmental bumpers 2 and 3 facilitate passage of the cars around acute curves.

It is believed that the many advantages of a mine car coupling constructed in accordance with the present invention will be readily understood, and although a preferred embodiment of the invention is as illustrated and described, it is to be

understood that changes in the details of construction and in the combination and arrangement of parts may be resorted to which will fall within the scope of the invention as claimed.

What is claimed is:—

In combination, a car coupling member having a chamber open at one side thereof and also having sockets the inner ends of which communicate with the chamber at opposite points, link retaining means intersecting said chamber 10 at a point midway between said socket ends, an open link receiving said link retaining means and movable laterally in said chamber and held against vertical deflection by the upper and lower walls thereof and projecting from the coupling 15 member to be engaged and held by a complementary coupling member, and springs housed in and projecting from said sockets and bearing against opposite sides of the inner end portion of the link.

JOHN L. DAY.
